R. MICHAELS

STORE FRONT CONSTRUCTION

Filed Sept. 22, 1923

Patented Mar. 15, 1927.

1,621,375

UNITED STATES PATENT OFFICE.

ROBERT MICHAELS, OF CHICAGO, ILLINOIS.

STORE-FRONT CONSTRUCTION.

Application filed September 22, 1923. Serial No. 664,206.

My invention relates to the so-called store front construction, which is the name by which the setting of large plate glass used for display windows, is known, and in particular it relates to the hollow type, that is, to the type whose inner and outer glass-engaging members are shells of sheet metal, usually copper.

My object, as achieved in what I consider now the best embodiment of my invention, is a store front construction inexpensive of manufacture, of extreme simplicity, maximum glass safety, and maximum drainage and ventilation with little or no inward passage of dust.

My invention consists in whatever is described by or is included within the terms or scope of the appended claims.

In the drawings:

Fig. 1 is a perspective view of a portion of a sill and a side jamb, illustrating one embodiment of my invention;

Fig. 2 is a vertical section thereof; and

Fig. 3 is a vertical section through the sill portion of another embodiment of my invention.

Fig. 4 is a detail view.

Briefly described, my invention, as shown in the drawings, comprises hollow members of sheet metal, preferably, though not necessarily, copper, that, respectively engage the glass on the outer side, and the inner side, the outer member for convenience being hereinafter termed the "sash", and the inner member being termed the "gutter", and which members are of identical construction on all four sides of the glass, namely sill, side jambs and head jamb.

Referring now in detail to what appears in Figs. 1 and 2, the sill 10, is, as is common, of wood, and upon its top set back from the front is a stop 11 of wood, and the side and head jambs have corresponding construction. The sill has its outer face and top covered with a copper covering 12, which at the rear has a vertical flange that covers the face of the stop 11, so that all wood surfaces that require protection are thereby protected.

The sash comprises a base 13 with vertical flanges 14 spaced a substantial distance one in advance of the other, whose edges engage the sill or jamb and an inwardly extending inclined or oblique member 15, that reaches from the outer flange 14, to the glass 16 which it engages by a lip 17, and

by an inwardly inclined wood screw 18, the sash, by indirect pressure brought to bear upon the oblique member 15, is made to exert a positive yet resilient pressure against the outer side of the glass to clamp it against the gutter on the inside. The oblique member 15 is given the contour of a molding to enhance its appearance and to render it elastic between its front flange 14 and its glass-engaging lip.

The wide bearing afforded by the sash base makes the sash self-sustained, with a firm support that prevents any slip or rocking and thus assures a firm hold of the sash on the glass. Although the bearing is a wide one yet as the base has contact only upon the edges of the flanges with the surface upon which the base rests any trouble in close fitting of the base upon its supporting surface due to any irregularities in the latter cannot occur as would be the case with a flat surface of an area reaching from one flange to the other; a mere line or edge contact which the flanges afford enables a tighter or closer fit, not only because the unit pressure from a mere edge is greater than that which can be secured from a surface of extended area but because of the yield or "give" of the metal between the flanges.

Holes 19 are provided at intervals through each flange 14, for ventilation, and in the case of the sill, for drainage, and these holes are staggered so that no dust can pass directly through the holes in both flanges, but it is trapped between them, for there can be no direct currents of air through the base, which, with the diminution of the force of the flowing air, by reason of its circuitous course, hinders the passage of dust.

The arched form of the base enables the provision of an upstanding flange 20 adjacent each screw 18 where it enters the wood and thus prevents water reaching the hole in the wood.

The gutter has a horizontal portion 21 that lies upon the stop, and reaches from the face thereof to the glass, and thence extends over the glass towards the edge thereof, and there has a flange 22 at right angles that lies parallel with the top portion 21 and reaches to the face of the stop, or the copper cover thereof, so that, as the gutter is secured by screws 23 to the stop, there are two parallel spaced portions at right angles to the glass that resist the inward pressure

of the glass rigidly or unyieldingly. Through these two parallel portions are holes 24 at intervals for ventilation and drainage (in the case of the still), and as there are these two portions the holes are staggered, as in the case of the sash base, and thus the force and direction of air currents, that would carry dust are diminished and changed.

The gutter has at its rear edge a hollow bead 25 that forms a barrier to water tending to pass to the top of the stop that has no protecting covering.

The holes in the top or outer member 21 have an inturned flange 26, that so directs water from the gutter that it is kept from flowing along the underside of the portion 21 to the joint at the top of the stop.

In the form of my invention shown in Fig. 3, the sash 27 is the same as in Figs. 1 and 2, but the gutter and sill cover are different, the sill cover 28 not reaching to the front of the stop 29, but the latter is covered by a flange 30 from the gutter 31, and the latter has a sub-gutter 32, formed by vertical flanges and a base.

I claim:

1. Window construction having a glass-engaging hollow sash of sheet metal provided with a base extended a substantial distance in the direction towards the glass, and having an obliquely extending portion reaching from the outer side of the base towards the glass, said obliquely extending portion and said base being joined and the base being plane and having at its outer and inner edges vertical flanges, and downwardly and inwardly extending screws passing through alining holes in said obliquely

extending portion and said base, the screws having heads to engage and exert clamping pressure against said obliquely extending portion, the holes in the base being situated between said flanges.

2. Window construction as in claim 1 having a bearing surface for the flanges engaged by the flange edges, the portion of the base between the flanges being spaced from such surface.

3. Window construction as in claim 1 in which the flanges at the outer edge is of double thickness, with the two thicknesses in side by side contact.

4. Window construction comprising a sash and an opposing member of sheet metal that has a portion extending horizontally inward from the glass, a supporting surface over which such portion extends and upon which it bears, said horizontally extending portion terminating in a hollow bead that extends transversely of the window, and said sheet metal member having next the glass a vertical glass engaging portion that extends downwardly from said horizontally extending portion, the latter between said bead and said vertically extending portion being plane, and said sheet metal member having a horizontally extending portion that terminates in a free edge and a vertical surface against which such free edge bears, whereby inward pressure on the glass is transmitted through said last named horizontally extending portion to the vertical surface with which its free edge contacts.

In testimony whereof I hereunto affix my signature.

ROBERT MICHAELS.
